UNITED STATES PATENT OFFICE.

JOHN H. CAMPBELL, OF DETROIT, MICHIGAN.

STEAM-GENERATOR.

SPECIFICATION forming part of Letters Patent No. 716,187, dated December 16, 1902.

Application filed December 16, 1901. Serial No. 86,050. (No model.)

To all whom it may concern:

Be it known that I, JOHN H. CAMPBELL, a citizen of the United States, residing at Detroit, in the county of Wayne, State of Michigan, have invented certain new and useful Improvements in Steam-Generators; and I do declare the following to be a full, clear, and exact description of the invention, such as will enable others skilled in the art to which it appertains to make and use the same, reference being had to the accompanying drawings, and to the figures of reference marked thereon, which form a part of this specification.

15 This invention relates to a steam-generator; and it consists in the construction and arrangement of parts hereinafter fully set forth, and pointed out particularly in the claims.

The objects of the invention are to produce 20 a steam-generator of comparatively simple and inexpensive construction in which the arrangement is such as to provide a rapid and constant circulation of water throughout the entire boiler, so as to maintain all parts at a 25 uniform temperature; to provide amply for expansion and contraction, so that no joints are effected by any change of temperature and a rupture of any of the pipes is obviated; to provide for an ample supply of water; to 30 the steam-generating coils, so as to obviate the possibility of the coils becoming dry and burning out; to provide a mud-pipe which receives the impurities deposited from the water, so positioned as to be free from the action of the fire, and to maintain a uniform 35 temperature of the water in the generating-coils, so as to relieve the boiler from the destructive strain due to unequal expansion.

The above objects are attained by the structure illustrated in the accompanying drawings, in which—

Figure 1 is a perspective view of my improved boiler with the casing removed. Fig. 2 is a vertical central section through the 45 boiler and casing, the steam and water dome appearing in elevation and a portion of said dome being broken away to show connection of steam-coils therewith. Fig. 3 is a horizontal section through the boiler as on line 3 3 50 of Fig. 2. Fig. 4 is a plan view of a baffle-

plate located between the generating-coils and the top of the casing.

Referring to the characters of reference, 1 designates the mud-pipe, consisting of the parallel side sections connected by the transverse section at the rear. The grate 2 is supported between the side sections of the mud-pipe upon the transverse bars 3, whose ends are in turn supported in the brickwork of the casing. Located at either side of the fire-space are the side coils 4, comprising a series of connected loops. The lower ends of said coils are connected by means of the fittings 5 with the side sections of the mud-pipe, while the upper ends of said coils are 65 connected by the short pipe-sections 6 with the upper portion of the steam and water dome 7. Said side coils are also connected with the bottom of said dome by means of the lateral pipes 8, leading from the T-couplings 9.

Interposed between the side coils 4 is a series of coils 10, located above the fire-space and around which the products of combustion pass. These coils 10 are connected at their 75 lower ends with the bottom of the dome 7 through the lower cap 11 of said dome, as shown in Figs. 2 and 3, and with the top of the dome by the elbows 12, as shown in Figs. 1 and 2, by which arrangement each individual coil is separately connected to the dome at its opposite ends, the lower ends of said coils communicating with the water-space of the dome and the upper ends of said coils communicating with the steam-space. As 85 the dome is filled with water to a point below the entrance of the upper ends of the coils therein, a constant and full supply of water is at all times furnished to said coils, so that no matter how rapid the circulation therethrough 90 nor what amount of steam is being generated therein said coils can never become dry through the exhaustion of water therefrom. At the same time the circulation of water through said coils is so rapid as to prevent 95 the accumulation of sediment. The upper end of the dome 7 affords a space for the steam, and leading from the cap 13 thereof is a steam-pipe 14, which is connected with the heating system. The return-pipe from the 100

heating or circulatory system is indicated at 15 and is connected at its lower end through a fitting 16 with the mud-pipe. Communicating with the bottom of the dome is a three-way fitting 17, from which lead the side pipes 18, that connect at their lower ends with the opposite side sections of the mud-pipe, and the rearwardly and downwardly extending pipe 19, which communicates at its lower end 10 with the rear section of said mud-pipe. This arrangement maintains a full supply of water in the mud-pipe and at the same time affords a free passage for the sediment from the dome.

It will be observed that all of the coils of 15 the generator communicate at one end with the water of the dome and at the other end with the steam-space thereof, whereby the water in all of said coils is of uniform temperature, thereby obviating unequal expansion, relieving the boiler from the strain incident thereto. By maintaining the water in 20 all of the coils at an even temperature the cooling of the water in any part of the boiler is obviated, and the generating of the steam 25 is not interfered with by the introduction into the circulation of water at a low temperature from some part of the boiler remote from the heating-space, as is common in many water-tube boilers.

30 The boiler is inclosed in a suitable casing 20, (illustrated in Fig. 2,) preferably of brick, and crossing the rear of the fire-space is a bridge-wall 21, which prevents the caloric current from passing to the rear and directs 35 it upwardly through the coils above the fire-space and around the dome. Crossing the top of the case transversely is a baffle-plate 22, which embraces the dome and stands at a short distance above the coils. Said plate 40 is provided at its two front corners with draft-openings 23 and with a semicircular opening 24 around the dome, through which the elbow connections of said coils extend and which also affords a passage from the draft. This 45 baffle-plate serves to prevent a too-rapid passage of the caloric current through the boiler and causes it to become distributed more evenly throughout the heating-space. Above the baffle-plate is a chamber 25, and communicating with said chamber is an opening 26, which leads to the stack.

50 A water-column 27 is provided, which is connected through the pipe-section 28 with the mud-pipe and by the pipe-section 29 with the steam-pipe 14. A steam-gage 30 is also connected with the pipe 29, as well as a safety-valve 31, which parts may be of any suitable construction.

55 It will be observed that there is considerable steam-space 32 within the upper end of the dome above the point of entrance of the generating-coils therein, so that a steam-chamber is formed of such area and of such height above the water as to prevent the entrance of the water into the pipe of the cir-

culatory system with the steam which passes therethrough.

Below the grate is a suitable ash-pit 33, to which access is afforded through the door 34.

The stoke-door is indicated at 35, through 70 which fuel is supplied to the combustion-chamber. Above the stoke-door is a large door 36, affording access to the steam-generating coils for the purpose of cleaning them from any accumulation of soot.

75 The system may be fed by introducing water into the return-pipe 15 or into the pipes of the heating system at any suitable point.

Having thus fully set forth my invention, what I claim as new, and desire to secure by 80 Letters Patent, is—

1. In a steam-generator, the combination of a steam and water dome, a mud-pipe connected therewith, a series of steam-generating coils comprising united horizontal pipe-sections arranged side by side and communicating at their lower ends with the water-space of said dome and at their upper ends with the steam-space thereof, all of said coils having independent and equal access to the water-supply and equally free communication with the steam-space of the dome.

2. In a steam-generator, the combination of a steam and water dome, a mud-pipe, side coils communicating at their lower ends with the mud-pipe and at their upper ends with the steam-space of said dome, said side coils also communicating with the water-space of said dome, a series of steam-generating coils consisting of horizontal and vertical pipes 100 united by bends at their ends interposed between said side coils, all of which communicate independently with the water-space of said dome at their lower ends and with the steam-space of said dome at their upper ends and a 105 pipe, connecting the lower end of said dome with said mud-pipe.

3. In a steam-generator, the combination of a steam and water dome, a series of coils comprising a plurality of vertical loops arranged 110 side by side and composed of united horizontal pipe-sections, said coils communicating at their lower ends with the water-space of said dome and at their upper ends with the steam-space therein, each of said coils having free 115 and independent communication with the dome at its opposite ends, the steam-space of said dome rising above the point of entrance of the upper ends of the coils therein, a grate and fire-space below said coils and means for 120 directing the caloric current around said coils and dome in its passage to the stack.

4. In a steam-generator, the combination of a dome, a mud-pipe comprising parallel side sections and a transverse rear section connecting said side sections, the pipes connecting said side sections and said rear section of the mud-pipe with the bottom of said dome, side coils communicating at their lower ends with the mud-pipe, at their upper ends 130

with the upper end of the dome and having a pipe connection with the bottom of the dome, a grate within the area described by the mud-pipe, a series of steam-generating coils consisting of horizontal and vertical pipes united by bends at their ends located between said side coils above said grate, each of said steam-generating coils having independent communication with the bottom of the dome at their lower ends and a like com-

munication with the top of the dome at their upper ends and a suitable casing embracing said coils and dome.

In testimony whereof I sign this specification in the presence of two witnesses.

JOHN H. CAMPBELL.
